KNITTING MACHINE OF THE OPPOSED
NEEDLE BED TYPE

Frederick Edward Deans and Carlyle Herbert Wainwright, Leicester, England, assignors to The Bentley Engineering Company Limited, Leicester, England

Application April 1, 1946, Serial No. 658,800
In Great Britain April 18, 1945

4 Claims. (Cl. 66—14)

1

This invention concerns knitting machines of the opposed needle bed type, especially circular knitting machines having opposed needle cylinders. In such machines it is desirable that the beds shall be closely adjacent to one another, which renders it difficult to accommodate elements in, or that are movable into, the gap between the margins of the two beds. Specifically, in the case of opposed cylinder machines it is difficult to apply wrap-thread mechanism there-to, because the comparatively wide space which must be left between the two cylinders to permit of the necessary movements of the wrap thread fingers leaves the needles unsupported for a considerable distance and jeopardises the certainty of their transfer from one cylinder to the other, and the undesirably great distance between the verge ring of the upper of rib cylinder and the knitting level is detrimental to the quality of the rib fabric. These are draw-backs that the present invention seeks to obviate.

The invention, in its broadest aspect, provides in or for a knitting machine of the opposed needle bed type, a needle bed having trick walls constituted by individually-slidable blades capable of projection and retraction at the margin of the bed. Preferably, this bed has a plurality of grooves, and a blade longitudinally slidable in each such groove but standing proud thereof whereby the space between successive blades forms a needle trick the walls of which are constituted by the blades themselves.

The invention further provides a knitting machine of the opposed needle bed type and particularly a superimposed or other opposed needle cylinder machine, having wrap-thread mechanism including at least one wrap-thread finger movable at a wrapping station in the space between the adjacent margins of the two beds to supply wrap thread to at least one needle, needle-trick walls in at least one of the beds constituted by individually slidable blades capable of projection and retraction at the margin of the bed, and operating means for said blades arranged to retract them at the wrapping station to provide room for the movements of the wrap finger. This machine may have a stitch cam, and means for projecting the blades to an abnormal extent at the stitch-drawing point. In order that the blades may maintain a normal position, without retraction, when wrap stripping is not taking place, the operating means may be capable of being rendered inoperative.

The foregoing and other features of the invention set out in the appended claims are incor-

2

porated in the construction which will now be described (as an example of the application thereof to a superimposed needle cylinder machine wherein double-ended latch needles are movable by sliders from one cylinder to the other in known manner), with reference to the accompanying drawings in which—

Figure 1 is an elevation of the top needle cylinder and cam box, partly broken away and in section;

Figure 2 is a development of the cams of the top box and also shows a sliding blade or needle-trick wall.

The illustrated machine is of the known type having a lower or plain cylinder 1 and an upper or rib cylinder 2 with cam box 3, these cylinders being equipped with double-ended needles 4 movable by sliders 5. The sliders are operable by cams, to cause the needles to work in either cylinder in the production of rib or plain stitches and to transfer the needles from one cylinder to the other so that the character of the rib structure may be varied or plain fabric may be produced. Machines of this type are well known and need no further description or illustration herein.

This machine is equipped with wrap-thread mechanism which comprises at least one and preferably a plurality of wrap-thread fingers (of which a representative finger is indicated at 6) which are suspended within the upper (or rib) needle cylinder 2 and are actuated by appropriate mechanism 7 so that as they reach a wrapping station in the region of the bracket W. S. in Figure 1 each one or each selected one is swung so that its lower thread-guiding end 6a moves outwards between the two cylinders into the attitude shown in Figure 1, moves sideways past at least one needle 4, and then retires so that as a result of these movements its thread is wrapped around at least one needle. It will be appreciated that in these movements a portion of the finger 6 passes over the head of at least one needle positioned in the bottom cylinder 1 and that in order to permit of this the lower margin of the top cylinder 2 must be positioned a greater distance above the top margin of the bottom cylinder (and above the sinkers) than is necessary in a machine not equipped with wrap-thread mechanism, and that this large gap is undesirable.

Accordingly the top or rib needle cylinder 2 is formed with tricks 8 to accommodate a series of slidable blades 9 which stand proud of the tricks and accommodate the sliders and rib needles between them so that in effect these blades 9 con-

stitute slidable trick walls. In their normal position (which they occupy throughout the major portion of each revolution and in which they are shown in the left hand portion of Figure 1) the lower ends 9a of these blades protrude well below the margin of the top cylinder 2 so that the gap between the two beds is reduced to a minimum, but at the wrapping station W. S. they are temporarily retracted (raised) to give an increased gap which affords the necessary room for the movements of the wrap fingers 6. The lower ends 9a of these blades 9 provide edges over which the rib loops are drawn and so permit the usual verge ring in the top cylinder to be dispensed with; said ends are thinned down (either by being stepped, as shown, or tapered) to give the increased trick width necessary to permit a rib loop to be drawn into the trick. In Figure 1, for the sake of clarity the blades 9 are shown as being very thick—as in a coarse gauge machine.

The movement of the blades 9 may be so controlled that when wrapping is not taking place (e. g., in the heel or toe) they remain in the lower position, and they may be so projected at the rib stitch drawing point that a rib stitch cam 25 may be employed having a much easier angle than is usual.

The blades 9 are controlled by means of butts 10 and cams, which are preferably located above the cams 11 of the top sliders 5. In order that the blade-operating cams may be close to the exterior periphery of the cylinder, the outer edges of the blades are cut back above the sliders (i. e., the upper ends of the blades are of reduced radial width) and the butts 10 are provided on this cut-back part. It is preferred that each blade shall have two spaced butts or their equivalent between which a strip-like or rib-like cam or succession of cams on the cam box engages so that the blades are always held under control without the complication of two sets of cams defining between them a track in which a single butt travels. Thus the butts 10 and steps or shoulders 12 travel respectively above and below a rib-like or strip-like series of cams 13, 45 14, 15, 16 and 17 by which (except by cam 16) the blades 9 are locked against endwise movement; while travelling over cam 16 the butts 10 are strictly guided between this cam and cam 19. The cam 16 is located in the region of the 50 wrapping station W. S. and is of reduced thickness (i. e., its inner surface is spaced radially outwards from the external periphery of the upper bed) to permit the blades 9 to be elevated by a movable cam 18, which is only inserted 55 when wrap stripping is to take place, to the upper cam 19 which engages between butts 10 and shoulders 12 to lock the blades in their elevated position. The blades are lowered by cam 20 acting on butts 10.

The rib stitch cam, which acts on the sliders of the top cylinder to draw rib loops, is indicated at 21. At the stitch drawing point the blades 9 are lowered below their normal position by a down-throw cam 22 (which may be adjustable vertically so that it will lower the blades to a variable amount below their normal position) to bring the two draw edges for the rib and plain loops as close together as possible, but the blades remain in their normal position right up to the stitch drawing point so as not to ob-

struct the feed of the yarn to the needles. As in this construction the loops are drawn by the conjoint action of the rib needles and the draw edges on the blades 9, moving in opposite directions, the angle of the rib stitch cam 21 can be made much easier than when, as is usual, the loops are drawn over fixed draw edges by the motion of the needles solely.

We claim:

1. In a circular knitting machine of the opposed needle cylinder type having double headed needles, sliders in the two cylinders for operating the needles and for effecting their transfer between the two cylinders, and cams, between which and the cylinders relative rotation takes place, defining races around each cylinder for operating the sliders; the combination of an upper cylinder having a plurality of circumferentially-spaced longitudinal grooves, a blade slideable longitudinally in each groove but standing proud thereof whereby each space between the successive blades forms a trick, for accommodating a slider and its needle, the walls of which trick are constituted by the blades themselves, operating butts on the upper ends of the blades, and a cam race, disposed above the upper cam race for the sliders, for engaging the butts of the blades and for projecting said blades one after another towards the lower cylinder and for retracting them one after another.

2. A machine according to claim 1, having the outer edges of the blades cut back above the sliders and having the butts provided on the cut-back edges.

3. In a circular knitting machine of the opposed needle cylinder type having double headed needles, sliders in the two cylinders for operating the needles and for effecting their transfer between the two cylinders, and cams, between which and the cylinders relative rotation takes place, defining races around each cylinder for operating the sliders; the combination of at least one yarn feeder movable, at a feeding station, between the adjacent margins of the two cylinders and across the needle circle, a plurality of circumferentially-spaced longitudinally-extending grooves in the periphery of the upper cylinder, a blade slideable longitudinally in each groove but standing proud of the periphery of the cylinder whereby each space between successive blades forms a trick, for accommodating and guiding a slider and its associated needle, the walls of which trick are constituted by two successive blades a butt on each blade, draw edges on the lower ends of the blades, and a cam race, disposed around the upper cylinder above the top race for the sliders, for engaging the blade butts to lower the blades individually in their tricks and to raise them individually at the feeding station.

4. A machine according to claim 3, having wrap stripe mechanism comprising a wrap stripe finger constituting the aforesaid feeder and having a thread-guiding end, and means mounting the finger within the upper cylinder for movement of its thread-guiding end, at said station, outwards across the needle circuit, sideways past a group of needles, and inwards across the circle.
